US0D1068877S

(12) **United States Design Patent** (10) Patent No.: **US D1,068,877 S**
(45) Date of Patent: ** Apr. 1, 2025

(54) **BENDING MACHINE**

(71) Applicant: **TRUMPF SE + Co. KG**, Ditzingen (DE)

(72) Inventor: **Dina Gallo**, Stuttgart (DE)

(**) Term: **15 Years**

(21) Appl. No.: **35/516,505**

(22) Filed: **Feb. 28, 2022**

(80) **Hague Agreement Data**

Int. Filing Date: **Feb. 28, 2022**

Int. Reg. No.: **DM/219391**

Int. Reg. Date: **Feb. 28, 2022**

Int. Reg. Pub. Date: **Mar. 3, 2023**

(30) **Foreign Application Priority Data**

Sep. 27, 2021 (EM) 008707467

(57) **CLAIM**

The ornamental design for bending machine as shown and described.

DESCRIPTION

1. Bending machine
2. Bending machine
3. Bending machine
4. Bending machine
- 1: Perspective
- 2.1: Front
- 2.2: Back
- 2.3: Top
- 2.4: Bottom
- 2.5: Left
- 2.6: Right
- 3: Perspective
- 4.1: Front
- 4.2: Back
- 4.3: Top
- 4.4: Bottom
- 4.5: Left
- 4.6: Right

(Continued)

The broken lines depict portions of a bending machine that form no part of the claimed design.
